Primary Examiner — Kelley Donnelly(74) *Attorney, Agent, or Firm* — Leanne Taveggia Farrell; Westman, Champlin & Kelly, P.A.(57) **CLAIM**

I claim the ornamental design for a display shelf, as shown and described.

DESCRIPTION

FIG. 1 is a perspective view of a first embodiment of a display shelf;

FIG. 2 is a front view thereof;

FIG. 3 is a top view thereof; and

FIG. 4 is a side view thereof.

FIG. 5 is a perspective view of a second embodiment of a display shelf;

FIG. 6 is a front view thereof;

FIG. 7 is a top view thereof; and,

FIG. 8 is a side view thereof, the opposing side being a mirror image.

The broken lines shown in the drawings are included for purposes of illustrating portions of the display shelf and form no part of the claimed design.

1 Claim, 8 Drawing Sheets# US D680,353 S
